(57) **CLAIM**

The ornamental design for a tire, as shown and described.

DESCRIPTION

FIG. 1 is a front right perspective view of a tire showing our new design, it being understood that the tread pattern of the tire repeats circumferentially about the outer circumference and shoulder of the tire;

FIG. 2 is a right side view thereof;

FIG. 3 is a left side view thereof;

FIG. 4 is a rear elevation view thereof; and,

FIG. 5 is a front elevation view thereof.

The broken lines shown in the drawings illustrate portions of the tire that form no part of the claimed design.
